UNITED STATES PATENT OFFICE.

MARMEON B. WRIGHT, OF TRAVERSE CITY, MICHIGAN.

ADJUSTABLE CAR-STAKE FOR PERMANENT USE ON LOGGING-CARS.

No. 907,547.

Specification of Letters Patent.

Patented Dec. 22, 1908.

Application filed April 17, 1907. Serial No. 368,789.

To all whom it may concern:

Be it known that I, MARMEON B. WRIGHT, a citizen of the United States, a resident of Traverse City, county of Grand Traverse, 5 and State of Michigan, have invented an Adjustable Car-Stake for Permanent Use on Logging - Cars, of which the following is a specification.

My invention consists in the manner of 10 constructing and fastening together stake and stirrup by means of a long single link permanently, yet adjustable at will. Stake can be placed in stirrup or allowed to swing along side of cars when not in use. Stake is 15 made to taper slightly on three sides, all that part entering stirrup, so as to fit the stirrup when fully set in; side of stake fronting cars is straight, causing stake to stand perpendicular when set into stirrup. Stake is 20 bound on the sides with malleable cast iron or steel the entire length, as represented in the drawings. Stake may be all of iron or steel. Stirrup is made tapering, being 25 larger at top than at bottom so as to fit the stake and allow the stake to become loose and easily lifted out by a slight stroke upwards on lower end of stake, causing stake to fall away from logs on the car. The single 30 link attachment which is the means of making the stake and stirrup a permanent combination, and admits of the adjustability of the stake, and its permanent use on logging cars is made fast to stake by means of an 35 eyebolt through which the link passes, the bolt passing through the stake near the part entering the stirrup. The link is fastened to stirrup by means of a slot or groove made inside of upper stirrup flange, deep enough to receive the link, allowing the top staple 40 bolt that goes round stirrup and fastens it to

the cars to pass through the link so as to allow link to slide up and down a sufficient distance to allow stake to be placed in or lifted out of stirrup at will, making stake, stirrup and link a permanent, yet adjustable combination. 45

The object of this invention is to permanently overcome the expense and the annoyance of using the unsafe, temporary wooden stake on logging cars. 50

Figure 1 shows a front view of the stirrup link and stake in the stirrup. Fig. 2. is a side view of the same elements. Fig. 3. shows the stake out of the stirrup and suspended by the link. 55

In the drawings are letters, A. B. C. D. used to designate the several parts or pieces of my invention.

Letter A. is to designate stake which has been fully described above as to its construction and purpose. Letter B designates the link, the means connecting the stake and stirrup. Letter C designates stirrup which also has been described as to its construction so as to admit of being attached to 60 stake A by means of the link B, the letters D. D. designate the side of car to which the combination stirrup, stake and link are fastened to show their proper positions when in and out of use on logging car. 65

In conclusion I claim—

The combination of a stake, a stirrup and a single link connecting the stake with the upper edge of the stirrup, substantially as described. 70
